UNITED STATES PATENT OFFICE

2,662,334

DENTURE SIMULATING TOY

Irving H. Fishlove, Chicago, Ill.

Application November 14, 1949, Serial No. 127,620

1 Claim. (Cl. 46—1)

1

My invention relates to a novelty amusement device and more particularly to an amusement device in the representation of a set of human or animal teeth and a tongue, and arranged to simulate the actions of the same.

One of the objects of my invention is the provision of an amusement device in the representation of a set of human or animal teeth and tongue, the teeth being adapted to be actuated to be opened and closed and the tongue cooperating with said teeth to project forwardly when said teeth are open and to retract inwardly when said teeth are closed.

Another object of my invention is the provision of a device of the foregoing character which is simple and economical to manufacture and which has a high degree of amusement value.

Other and further objects and advantages of my invention will become apparent from the following description when considered in connection with the accompanying drawings in which:

Fig. 1 is a perspective view of a device in accordance with my invention, showing the teeth in normal or opened position.

Fig. 2 is a top plan view thereof.

Fig. 3 is a longitudinal cross-sectional view taken substantially on line 3—3 of Fig. 2.

Fig. 4 is a view similar to Fig. 3, but showing the teeth in closed position.

Fig. 5 is a view looking in the direction of the arrows 5—5 of Fig. 4.

Referring to the drawings, my invention is shown in the representation of a set of human teeth. It will be understood however, that the teeth may be representative of other living creatures, including animals. My device comprises upper and lower sections 10 and 11 hinged together, as will be hereinafter described, and arranged to simulate the action of the upper and lower jaws of a human being or animal. The upper jaw section 10 includes a flat body portion 12 having a rearward straight edge 12a and a substantially arcuate edge 12b shaped to conform to the general configuration of a denture. Depending from the body portion 12 is a flange 14 substantially coextensive in length with the arcuate edge 12b of the portion 12. The flange 14 is preferably integral with the body portion 12 and is provided with a plurality of indentations or markings 13 which are intended to simulate interdental spaces between the simulated teeth 15. Extending upwardly from the body portion 12 and following the contour of the edge 12b thereof is a flange 16 which projects beyond

the plane of the flange 14 and is intended to be colored so as to represent the gum portion of the section 10. The said flange 16 continues rearwardly for a portion thereof and forms a top wall 17 which serves to lend a finished and more attractive appearance to the section 10. Depending from the portion 12 are two spaced lugs 18, each having a perforation. Disposed substantially medially of the lug 18 and depending from the body portion 12 is an arm 19 perforated at the free end thereof.

The lower jaw section 11 includes a body portion 21 shaped like body portion 12 and provided rearwardly thereof substantially along a medial line with a slot 22, the slot extending substantially from the mid point to the rearward edge of the body portion 21. The said body portion is provided with an offset portion 23 which extends under and around the slot 22 to provide a well 22a. An upstanding flange 24 is formed integral with the body portion 21 and is shaped complementary to the flange 14. The said flange is similarly provided with indentations or division lines 24a to simulate the interdental spaces between the teeth. Depending from the body portion 21 is a flange 25 which similarly to the flange 16 projects beyond the plane of the flange 24 and is colored to simulate the gum portions of the jaw section.

Suitably supported on the body portion 21 are a pair of spaced lugs 26 provided with perforations which are adapted to register with the perforations of lugs 18 to receive pins so as to pivotally connect the jaw sections 10 and 11 together. A spring 27 is connected to a suitable opening in the rearward portion of each of the sections 10 and 11 and serves to urge the said sections to open position, as shown in Figs. 1 and 3. A member 28 has a forward portion 29 shaped in the representation of a tongue and a rearward portion 30 bifurcated and disposed in angular relation to the portion 29. The ends of the furcations are perforated transversely to receive a pin which pivotally connects member 28 to the arm 19. As will be seen clearly in Figs. 1 and 5, the arm 19 is received between the furcations 30. An abutment 31 is formed on the inner side of the flange 24 and has its top surface 32 inclined for a purpose as will be hereinafter described.

The operation of my device should be apparent from the foregoing description but briefly stated it is as follows: In the normal non-operative position illustrated in Figs. 1 and 3, the jaw sections 10 and 11 are normally in open position

with the tongue portion 29 projected forwardly, as shown in Figs. 1 and 3, and resting on the flange 24. In order to operate the device, the device may be grasped with the hand so that the thumb is in engagement with the underside of jaw section 11 and two or more fingers in engagement with the top surface of the jaw section 10. Upon the application of pressure to bring the sections 10 and 11 together, the jaw section 10 is caused to move in a counter clockwise direction about its pivot as viewed in Fig. 4. The arm 19 will move correspondingly to the right and will draw therewith the member 28 so that when the flanges 14 and 24 are in engagement as shown in Fig. 4, the member 28 is completely retracted within the chamber formed by the two sections 10 and 11 with the free end of member 28 resting on inclined surface 32 of abutment 31. Upon release of any pressure tending to move the sections 10 and 11 into engagement, the spring 27 urges the said sections to the open position shown in Fig. 3. As the jaw section 10 pivots in a clockwise direction, the arm 19 is moved to the left as viewed in Fig. 3 and effects a corresponding movement of the member 28 which slides over abutment surface 32 and the top edge of the flange 24 until it reaches the position shown in Fig. 3 which corresponds to a maximum opening of the sections 10 and 11. Thus, upon alternate application and release of pressure tending to open and close the jaw sections the action of a human or animal jaw may be simulated accompanied with a forward projection of the tongue portion when the jaw sections are in open position and a retraction of the tongue portion when the sections are in closed position. It will be thus apparent that upon rapid opening and closing of the jaw sections 10 and 11 considerable amusement may be created.

I claim:

A hand held and operated amusement device comprising upper and lower elements in the representation of upper and lower dentures of a human being or animal, said elements being hinged rearwardly thereof each of said elements having an engaging surface forwardly of the hinge, one of said engaging surfaces adapted to be engaged by the thumb of a hand extending from the rear, the other of said engaging surfaces adapted to be engaged by a finger of the hand extending from the rear, a depending arm rigidly associated with said upper element and extending into the space of said lower element, a tongue element having a rearward downwardly directed angular extension hingedly connected at its free end to the end of said depending arm, said tongue element—when said upper and lower elements are in closed position—being fully retracted within the space defined by said upper and lower elements, said tongue element—when said upper element is pivotally moved to open position—being simultaneously projected forwardly.

IRVING H. FISHLOVE.
